CLAIM

I claim the ornamental design for a vehicle emergency lighting unit, as shown and described.

DESCRIPTION

FIG. 1: is a front elevational view of a vehicle emergency lighting unit showing my new design;

FIG. 2: is a rear elevational view thereof;

FIG. 3: is a top plan view thereof;

FIG. 4: is a bottom plan view thereof;

FIG. 5: is a side elevational view thereof, with the opposite side being a mirror image thereof; and,

FIG. 6: is a perspective view thereof.
